UNITED STATES PATENT OFFICE.

MARION W. STOMS, OF KANSAS CITY, MISSOURI, ASSIGNOR OF ONE-HALF TO LEIGH W. MORRIS, OF KANSAS CITY, MISSOURI.

CONDENSER.

Application filed July 21, 1921. Serial No. 483,553.

To all whom it may concern:

Be it known that I, MARION W. Stoms, a citizen of the United States, residing at Kansas City, in the county of Jackson and State 5 of Missouri, have invented certain new and useful Improvements in Condensers; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to a refrigerating apparatus and particularly to a condenser for translating a refrigerant from a vapor phase to a liquid phase.

A condenser is employed in conjunction 20 with a compressor for compressing the refrigerant vapor and forcing it into the condenser. There is a liquid receiver for receiving and storing the supply of the condensed refrigerant from the condenser, the 25 receiver discharging into an evaporator for absorbing the heat from the surrounding atmosphere, thus causing the liquid refrigerant to vaporize or gasify preparatory to being passed to the compressor, from which 30 it is again forced into the condenser so that it can be reduced to its liquid phase by cooling it below its critical temperature by a suitable cooling medium.

The condenser embodies a principle that 35 a gaseous refrigerant, such as ammonia, readily condenses into a liquid phase when introduced into a body of its own liquid which has been previously cooled, it being understood that the cooler the liquid, the 40 more readily the vapor will combine with it.

Broadly, the condenser consists of a plurality of double pipes, horizontally superimposed one above the other and divided into three sections, which I term a flooded section, 45 a condenser section and a final cooling section. The inlet of the condensing section connects directly with the vapor supply from the compressor and with the flooded section while the outlet for the condensing section 50 connects with the flooded section and with the final cooling section.

In this description the terms "gas" and "vapor" are used interchangeably because the liquid may not expand above the vapor 55 phase or it may continue on to the gaseous

phase. The term "double pipe" is used to include one pipe inside a larger pipe, leaving an annular space between them, the smaller pipe constituting one conduit and the space between the small pipe and the larger pipe 60 constituting another conduit, each conduit being an independent circuit. The refrigerant passes through one conduit and the cooling liquid, generally water, passes through the other conduit and for the purpose of 65 illustration I have shown the smaller pipe as the cooling conduit and the space between the smaller pipe and the larger pipe the refrigerant conduit.

The novel features of the invention will 70 be specifically described hereinafter, reference being had to the accompanying drawings, in which —

Fig. 1 is an elevational view of a refrigerating system constructed in accordance with 75 my invention.

Fig. 2 is a perspective view of the condenser, parts being broken away to show the interior pipes, and

Fig. 3 is a sectional view through a slightly modified form of directional tube for leading in the refrigerant in the vapor phase to the manifold to combine it with the refrigerant in the liquid phase.

Referring to Fig. 1:

1 designates a gas compressor having an inlet at 2 and an outlet at 3. 4 is a receiver or refrigerant reservoir to receive the refrigerant in a liquid phase. 5 is a discharge for the receiver communicating with evaporator coils 6, which discharge into the compressor through the inlet 2. The liquid is drawn through the coil 6, absorbing the heat in the usual way and becoming automatically translated from a liquid phase to a gaseous 95 phase or vapor phase, in which state it enters the compressor 1. The compressed refrigerant in the vapor or gaseous phase is discharged through the port 3 into the pipe 7, which communicates with the coupling 8 for 100 the gas directional nozzle, as clearly shown in Figs. 1 and 2.

There are stop valves 9 and 10 for the pipes 7, which may be used to close off communication through said pipe. The directional nozzle 11 discharges into a condenser pipe 12, the lower end of which communicates with the flooded section of the condenser consisting of the pipes 13, 14, 15, 16 and 17. The top end 18 of the pipe 12 com- 110

municates with the lower pipe 19 of the condenser section, the condenser being shown as consisting of the pipe 19 and the pipes 20 and 21. The top of the condenser, that is, 5 the pipe 21, communicates with the top pipe 17 of the flooded section or reservoir through the medium of a pipe 22, whereby the refrigerant in the liquid phase divides and the amount of the liquid equal to that which has 10 been condensed from the gaseous phase to the liquid phase will pass upwardly through the pipe 23 to the top of the final cooling section of the condenser consisting of the pipes 24, 25, 26 and 27, from which the refrigerant in the liquid phase will discharge 15 through the pipe 28 into the receiver 4.

The final cooling section may be provided with a purge pipe 29, as will be well understood, and a drain pipe 30 may be provided 20 for the gas section so that the condenser may be drained and the contents may flow into the pipe 28 and pass into the receiver 4.

The pipes 13, 14, 15, 16, 17 and 19 are connected by one set of hollow elbows or 25 unions 31 and 20 and 21 may be connected by another set of hollow elbows or unions 31, and the pipes 24, 25, 26 and 27 may likewise be connected with similar unions or 30 elbows so that there may be a continuous passage of the refrigerant from the pipes 17 to 13 and 19 to 21 and a continuous flow through pipes 24, 25, 26 and 27 to the evaporating system.

The refrigerant is cooled by a cooling 35 conduit consisting of a pipe 32, which may be supplied with a cooling liquid, such as water or the like, the pipe being divided at 33 to provide a branch 34, passing through pipes 24, 25, 26 and 27, 21 and 20 from the 40 top to the bottom in the order named, and discharged at 35 into a flow-off pipe 36. The pipe 32 is also provided with a branch 37, which passes through the pipes 13, 14, 15, 16, 17 and 19 and passes through the pipe 38 45 into the flow-off pipe 36, as will be clearly seen in Fig. 2.

The branch 34 and the branch 37 of pipe 32 are each of considerably less diameter than the pipes which cover them so that an 50 annular space is formed between the inner pipes and the outer pipes which constitutes the conduits through which the refrigerant flows. The branch pipes 34 and 37 respectively are, for mechanical expediency, constructed of a plurality of sections connected by the elbow or U-shaped couplings 39 and 40 outside the larger pipes so that there can be a continuous flow of cooling water through the final cooling stage and through 55 the pipes 20 and 21 of the condenser from the pipe 34 to the pipe 36 and a correspondingly efficient flow of cooling water through the section of the branch pipe 37 in the pipes 13, 14, 15, 16 and 17 of the flooded section 60 and the pipe 19 of the condenser. The cool-

ing water passing through the inner pipes being at a lower temperature than the refrigerant, will carry off the heat so that the refrigerant can be translated from a gaseous phase to a liquid phase preparatory to 70 passing into the receiver, from which it is fed to the evaporator coils.

When the refrigerant is fed from the compressor in a gaseous or vapor phase, it will pass through the directional nozzle, past the 75 outlet in pipe 13 and lift the refrigerant in the flooded section into the pipe 12, where the liquid and gaseous refrigerant will combine so that when they enter the condenser, they will be in a saturated state or practically at what is termed the "dew point" although to some extent, they may be in a liquid or semi-liquid condition. The excess refrigerant, that is, the amount supplied from the compressor, will divide at the pipe 80 41 so that it may pass through pipe 23 into the top pipe 24 of the final cooling stage. The refrigerant, which has previously passed from the flooded section, will divide from the pipe 41 and pass into 22 and flow 85 back into the flooded section consisting of the pipes 13 to 17, both inclusive.

The refrigerant which has passed into the pipe 23 will discharge into pipe 24 through pipe 42, traversing the space between the pipe 34 and pipes 24, 25, 26 and 27, where the refrigerant will be finally cooled before it discharges into pipe 28 to enter the receiver 4. Therefore, the refrigerant to be directed to the evaporator coils will be 100 reduced to the final cooling temperature before it enters the receiver by the liquid which passes through the inner pipes. Such a construction eliminates the necessity for employing surface condensers in which a 105 flow of water is disposed over the top of the pipes into a trough, the cooling system being a closed system in contra-distinction to that class of condensers in which the water is flowed over the outside of the gas or refrigerant-containing pipe. 110

In Fig. 3 I have shown a slightly modified form of directional nozzle 11', which is in the form of an ejector to increase the velocity of the gas passing from the nozzle 115 thereof and therefore, increase the lift exerted upon the refrigerant in the liquid phase. In other respects the apparatus embodying the ejector nozzle will be substantially like that shown in Figs. 1 and 2.

It will be apparent that the device contemplates means whereby a constantly flooded section is provided so that there will always be an available supply of liquid to combine with the refrigerant in the gaseous or vapor phase before it enters the condenser and that the construction is so arranged that the amount of refrigerant in the liquid phase which is fed into the pipe 12 will always be returned back to the flooded section and 130

only the excess refrigerant in the liquid phase, that is, the amount which has been converted from the gaseous phase, passed from the compressor, will pass into the final 5 cooling section before entering the receiver 4.

A condenser constructed in accordance with my invention is simplified to the extent that the cooling liquid as well as the 10 refrigerant, is entirely carried by an enclosing conduit instead of being splashed or flowed over the exterior surface.

It will be observed that the pipes 22, 23, 15 41 and 42 constitute a manifold for controlling the flow of the refrigerant in the liquid phase for dividing the flow so that the flooded section will have its quota divided from the sum total consisting of the introduced liquid from the bottom of the flooded 20 section and the refrigerant in the gaseous phase from the pipe 7.

What I claim and desire to secure by Letters-Patent is:

1. A condenser for refrigerators comprising a plurality of connected pipes in the 25 form of a coil, divided into communicating sections, one of which is a flooded section, one a condenser section and the remaining one a final cooling section, arranged from the bottom to the top in the order named, the flooded section having its discharge communicating with the bottom of the condenser section, and its intake communicating with the top of the condenser section, the intake 30 for the final cooling section communicating with the top of the condenser section, and cooling pipes for the coils, one cooling pipe entering the top of the final cooling section and discharging from the condenser section 40 and the other pipe entering the bottom of the flooded section and discharging from the condenser section.

2. A condenser for refrigerators comprising a plurality of connected pipes in the 45 form of a coil, divided into communicating sections, one of which is a flooded section, one a condenser section and the remaining one a final cooling section, arranged from the bottom to the top in the order named, a 50 cooling water-receiving pipe entering the top of the final cooling section and discharging at approximately the middle of the coil, and a second cooling pipe entering the bottom of the flooded section and discharging approximately at the middle of the coil.

3. A condenser for refrigerators comprising a plurality of connected pipes in the 55 form of a coil, divided into communicating sections, one of which is a flooded section, one a condenser section and the remaining one a final cooling section, the flooded sec-

tion having its discharge communicating with the bottom of the condenser section and its intake communicating with the top of the condenser, means for connecting the top of the condenser section with the top of the final cooling section, and cooling pipes for the several sections, one of which enters the top of the final cooling section and discharges through one of the coils of the condenser section, and the other pipe entering the bottom of the flooded section and discharging through one of the coils of the condenser section.

4. A condenser unit for refrigerating apparatus comprising a plurality of connected pipes in the form of a coil, divided into communicating sections, one of which is a flooded section, one a condenser section and the remaining one a final cooling section, a pipe 75 into which the flooded section discharges, a gas pipe discharging into the said pipe and through it into the condenser section, a pipe having connection with the top of the final cooling section, a pipe connected to the 80 flooded section, and an intermediate pipe connected to the top of the condenser section and dividing its flow between the pipe for the final cooling section and the pipe for the flooded section, and cooling pipes entering 85 the top and bottom of the coil and traversing the same toward the bottom and top respectively, the two pipes discharging approximately midway of the coil.

5. A condenser for refrigerators comprising a plurality of connected pipes in the 90 form of a coil, divided into communicating sections, one of which is flooded section, one a condenser section and the remaining one a final cooling section, arranged from the bottom to the top in the order named, a pipe connecting the bottom of the flooded section with the bottom of the condenser section, a refrigerant gas pipe discharging into said 95 pipe, an ejector nozzle at the point of discharge of the gas pipe into said pipe, a manifold connected to the top of the final cooling section, to the top of the flooded section and to the top of the condenser, a discharge pipe at the bottom of the final cooling section, 100 cooling pipes entering the top of the final cooling section and traversing the coils to about midway of the group of coils, and a cooling pipe entering the bottom of the coils and traversing the lower walls and discharging 105 at about midway of the coils whereby initial cooling water will be introduced into the top of the final cooling section and the bottom of the flooded section.

In testimony whereof I affix my signature. 110

MARION W. STOMS.
